THROWER FOR TARGETS OR THE LIKE

Edward R. Reed, Dallas, Tex., assignor of one-half to
W. J. Langley, Dallas, Tex.

Filed Dec. 18, 1964, Ser. No. 83,082

Term of patent 3½ years

(Cl. D34—5)

FIG. 1

FIG. 2

FIG. 3

FIG. 5

FIG. 1 is a perspective view of a thrower for targets or the like, embodying my new design,

FIG. 2 is a side elevational view,

FIG. 3 is a top plan view,

FIG. 4 is a bottom plan view, and

FIG. 5 is a front end elevational view.

The dominant features of my design reside in the portions shown in full lines.

I claim:

The ornamental design for a thrower for targets or the like, as shown and described.
